UNITED STATES PATENT OFFICE.

GEORGE W. DONNING, OF STAMFORD, CONNECTICUT, ASSIGNOR TO
HARRY T. AMBROSE, OF ORANGE, NEW JERSEY.

TYPE-WRITER.

No. 826,487.

Specification of Letters Patent.

Patented July 17, 1906

Application filed June 27, 1904. Serial No. 214,131.

To all whom it may concern:

Be it known that I, GEORGE W. DONNING, a citizen of the United States, residing at Stamford, in the county of Fairfield and State of Connecticut, have invented certain new and useful Improvements in Type-Writers; and I do hereby declare the following to be a full, clear, and exact description of the invention, such as will enable others skilled in the art to which it appertains to make and use the same.

My invention relates to ribbon mechanism for type-writers, and more particularly to ribbon mechanism for a visible-writing type-writer of the character disclosed in my application for United States Letters Patent, Serial No. 107,471, filed May 15, 1902.

The object of my invention is to provide in a writing-machine a ribbon mechanism which may be termed "interchangeable" and which may be used in connection with a ribbon of a plurality of colors, or with a ribbon of a single color divided so that one portion may be used as a "record-ribbon" for record-work and another portion as a "copying-ribbon," (these ribbons being made in divisional strips longitudinally disposed,) or with a ribbon of but one kind and color.

A further object is to provide a ribbon-shifting device capable of shifting the ribbon widthwise to one position for a different path and reverse the feeding thereof and to a further point for a still different path or for a different color, and this without reversing the feed of the ribbon.

A further object is to provide means for reversing the feed of the ribbon and simultaneously therewith shift the ribbon widthwise to a predetermined position.

A further object is to provide means for shifting the ribbon widthwise to a predetermined position without reversing the feed, so that any one of a plurality of colors or sections of the ribbon may be brought into the path of the type.

A further object is to provide, in connection with a single multicolor ribbon, means for permitting continuous use of one of the colors thereof and for effecting reversal of the feed thereof without changing the color.

A further object is to provide an index-plate carrying locking and limiting devices for the ribbon-shifting mechanism.

A further object is to provide means for

disengaging the ribbon-feeding mechanism, thus stopping movement of the ribbon and presenting the ribbon temporarily stationary—that is, at the moment of printing.

A further object is to provide for such appropriate disposition of the parts that the greatest ease of manipulation shall be obtained and that the direction of shifting of the spools may indicate to the operator the direction of feed of the ribbon.

A further object is to provide means for elevating and depressing the ribbon at the printing-point during the operation of the machine and in any one of the widthwise shifts of the ribbon, thereby obtaining a visible surface while the operable parts of the machine are in their normal positions.

With these objects in view the invention consists in the novel construction, combination, and arrangement of parts described and claimed.

In the accompanying drawings, forming part of my specification, and in which like letters of reference indicate corresponding parts in the several views and illustrative of one of several embodiments of my invention, Figure 1 is a perspective view illustrating this particular embodiment of my invention applied to the traveling carriage of a type-writer. Fig. 2 is a view in transverse sectional elevation of the parts shown in Fig. 1.

Fig. 3 is a view in transverse sectional elevation, showing the parts at the opposite end of the type-writer from that illustrated in Fig. 2. Fig. 4 is a view in front elevation of the left-hand section of the type-writer. Fig. 5 is a plan view of the construction shown in Fig. 1.

Fig. 6 is a view in detail sectional elevation, on an enlarged scale, showing one ribbon-spool and the ribbon-guide with one of the type-bars in printing position. Fig. 7 is a view in side elevation, showing, detached, the ribbon-guide and its actuating connections. Fig. 8 is a view in end elevation, showing the combination ribbon-shifting levers, a portion of the side plate of the transversely-movable carriage being partly broken away more clearly to show the relation of said levers and their connections. Fig. 8^a is a similar view showing in dotted lines the parts in the normal position, as shown in Fig. 8, and in full lines the positions assumed by the parts when the short shifting-lever is moved with relation to the long lever E,

75

which latter remains as in Fig. 8, thereby shifting the ribbon to a different path without reversing the feed. Fig. 8^b is a similar view showing in dotted lines the parts in the same position shown in Fig. 8^a and in full lines showing the position assumed by the parts when the long lever is moved, carrying the short lever in the same relative position shown in Fig. 8^a, thereby shifting the ribbon to a different path and reversing the feed. Fig. 8^c is a similar view showing in dotted lines the parts in the position shown in Fig. 8^b and in full lines the position assumed by the parts when the short lever is moved, the long lever remaining in the same position shown in Fig. 8^b, thereby shifting the ribbon to a different path without reversing the feed. Fig. 9 is a view in detail side elevation, on an enlarged scale, showing a ribbon-spool, its supporting-bracket, and the reversing-lever. Fig. 10 is a bottom plan view of parts shown in Fig. 9. Fig. 11 is a front view, partly broken away, of the construction illustrated in Figs. 9 and 10. Fig. 12 is a detail view, on an enlarged scale, showing the shiftable plate and the spool-actuating pawls. Fig. 13 shows three detail views of the feed-lever. Fig. 13^a is a rear view of a portion of said feed-lever and parts at the forward end thereof. Fig. 14 shows in side elevation, plan, and rear elevation the feed-reversing lever; and Fig. 15 shows three detail views of the spool-supporting plate or bracket.

The ribbon-spools and their actuating mechanisms at both sides of the machine are similar. Hence it will be necessary to describe but one of them.

Referring to the drawings, (in which only enough of a complete type-writer is shown as to enable a clear comprehension of my invention,) *a* indicate ribbon-spools frictionally supported on tubular spindles *a*², carried by studs *a*³. The tubular spindles can advantageously be slotted and compressed longitudinally to cause them to bear against the ribbon-spools with sufficient pressure to engender the proper frictional contact. These spools are constructed for ready removal and interchangeability, and it is to be understood that I may have the ribbons when manufactured wound directly on said spools rather than, as the custom now is, to compel the operator to wind a fresh ribbon upon the non-removable spools when change is required. Another advantage is that as these ribbon-spools are removable and replaceable at will by the operator each operator may have a series of different colors or combination of colors or character (record and copying ribbons, for instance) for various commercial uses.

Ribbon-feed mechanism.—As illustrated, the ribbon *R* employed is carried on two spools, which are supported at opposite sides of the writing-point. In the drawings only a

single ribbon of two colors is shown; but it is to be understood that I contemplate also the use of a plurality of ribbons when required of the same color or of two or more colors. I may also where the single ribbon is employed have more than two colors or kinds in the one ribbon. In either event, whether a single or double ribbon is employed, the "ribbon element"—and this term is to be understood as covering either a single or a double ribbon—comprises a plurality of longitudinal regions *R' R²*, each of which comprehends a plurality of writing-paths.

A ratchet-wheel *a*⁴ is rigidly secured to or is integral with the spindle *a*² and is constructed to be engaged by two pawls—respectively a feeding and a locking pawl—*a*⁵ *a*⁶, there being springs *a*⁷ *a*⁸, respectively, to maintain the pawls in operative position on their supports. (See especially Figs. 4 and 11.) The feeding-pawl *a*⁵ is pivoted on the front face of one end of a feed-pawl arm *a*⁹, which is secured at its other end to a shiftable plate *a*¹⁰, sliding in guideways *a*¹¹ of an angularly-extending portion *a*¹² of a slide *a*¹³, movably supported by guides *a*¹⁴ on the type-writer side plate *A*. As will be seen in Figs. 4 and 12, the feed-pawl arm *a*⁹ extends somewhat beyond the edge of the plate *a*¹⁰ and is preferably curved to clear the spool-spindle. The shiftable plate *a*¹⁰ is cut away at *a*^{10x}, as shown in Fig. 12, so that in its sliding it will not impinge against the spool-supporting spindle *a*², which is secured to the angular portion *a*¹² of the slide *a*¹³. The locking-pawl *a*⁶ is preferably mounted on an idler-bracket *a*¹⁵, and as the shiftable plate *a*¹⁰ withdraws the feeding-pawl *a*⁵ from engagement with the ratchet-wheel *a*⁴ a stud *a*¹⁶ on said shiftable plate *a*¹⁰ bears against the locking-pawl *a*⁶ and withdraws it also from engagement with the ratchet-wheel, permitting free movement of the entire ribbon-spool in either direction, the spring *a*⁸ serving to hold the pawl constantly against said stud *a*¹⁶.

A feed-pawl-operating lever *B*, arranged in juxtaposition with and pivoted at *b* to the slide *a*¹³, is preferably formed, as shown in Fig. 13, to permit its free movement and is provided with a bent slotted end *b*²; Fig. 13, constituting a yoke for embracing a stud *a*¹⁷, which is carried by the back of the extending end of the feed-pawl arm *a*⁹ and projects through opening *a*^{12a} in member *a*¹², (see Fig. 13^a), the slot *b*² being elongated to permit movement of the stud *a*¹⁷ therein. As will be readily recognized by reference to the drawings, the pivotal centers of feed-pawl arm *a*⁹ and ratchet-wheel *a*⁴ are so relatively arranged and the radii of the arcs are so proportioned that the path of movement of the feed-pawl embraces the periphery of the ratchet-wheel, and therefore can coincide with it for but a short period of time. Hence the rotation of the carrier at any one time is

slight, and the parts are so disposed that the feeding movement has entirely ceased when the type strikes the ribbon. It will be understood, of course, that the lock-pawl engages with the ratchet-wheel to prevent retrograde movement thereof. The inner end of said lever B is pivotally connected at b^3 to an upwardly-extending link b^4 , pivotally connected at its upper end c to a horizontally-extending lever C. This lever C is suitably pivoted or supported at its rear end on a rod D and is connected to a universal bar E, which extends transversely to the other side of the carriage, where it connects with the same kind of a lever C^2 as C. A spring c^2 , attached to the rear end of the lever C, returns the same to normal position after actuation.

From the above description it will be clearly understood that upon actuation of the universal bar E by a type-bar impinging against it the lever C will be depressed, the link b^4 will simultaneously be actuated and rock the lever B on its fulcrum, and this will cause the feed-pawl a^5 to engage and rotate the ratchet-wheel, and thus the ribbon-spool with which the ratchet-wheel connects. It will be noted, as already pointed out, that the pawl a^5 is so arranged relative to the ratchet-wheel a^4 that it is removed from engagement with said wheel during the latter portion of its upward movement, due to larger radius through which the pawl swings with relation to the radius of the ratchet-wheel teeth and to the position of the fulcrum. This will be seen by noting in the drawings the fulcrum-point of feed-pawl arm a^6 , which practically gives the feed-pawl a^5 a tangential movement. By this means I effect a temporary or momentary retarding or stopping of the feeding of the ribbon at the moment that a type-bar is about to impinge upon it to imprint, and thus prevent filling up of said type with ink, &c.

Ribbon shift and feed reversing mechanism.—A cam-plate F is mounted in juxtaposition to the side plate A and is rigidly secured to a transverse rocker-shaft G, which projects through side plate A and also connects with the cam-plate F on the opposite side of the carriage and is provided with two cam surfaces or slots f and f^2 , Figs. 1, 2, 3, and 8. This cam-plate is preferably disposed contiguous to the slide a^{13} and through interposed connections effects movement thereof. A bell-crank lever H, pivoted to the side plate A, carries at one end a stud h , engaging a slot a^{16} in the slide a^{13} , and at its other end carries a stud h^2 , engaging the cam slot or surface f . A rocker-lever I is fulcrumed at i on the slide a^{13} . The rear end of this lever I carries a stud i^2 , which engages with the cam slot or surface f^2 in the cam-plate F, and the forward end of said lever is formed with an enlarged bent end or offset i^3 , provided with an obliquely-curved slot i^4 and a vertically-

arranged guide-slot i^5 contiguous to each other. The obliquely-curved slot i^4 embraces a stud a^{19} , projecting through and sliding in a slot i^{20} in the slide a^{13} and carried by the plate a^{10} . The guide-slot i^5 engages a stud a^{21} , carried on the back face of angled extensions a^{12} of said slide a^{13} . Now, as will be obvious, when the rear end of rocker-lever I is forced downward by the cam-plate F the forward slotted bent end will rise and its two slots i^4 and i^5 will ride, respectively, upon the studs a^{19} and a^{21} , and by reason of the oblique direction in which said stud a^{19} is caused to move (the slotted end of said lever being held steady and in place by the stud a^{21} riding in the slot i^5) the shiftable plate a^{10} will be reciprocated in its guideways a^{11} far enough to carry the pawls out of engagement with the ratchet-wheel a^4 . By referring to the direction of inclination of slot i^4 , as illustrated in Fig. 14, it being understood that the direction of inclination of slots i^4 in the two levers I at opposite sides of the writing mechanism is the same, while the two sets of pawls are located at opposite sides of the ratchet-wheels, it will be seen that the foregoing description applies to the right side of the machine. At the same time that the pawls at the right side of the machine are being shifted out of engagement with their ratchet-wheel the pawls at the left of the machine take into the teeth of the corresponding ratchet. The peculiar construction of cam-plate F and the engagement therewith of feed-reversing lever I insure that the pawls will be locked in either of their shifted positions. In addition there is provided distinct locking means, which will presently be described. Of course when levers I are oscillated in the opposite direction this will cause the shiftable plates a^{10} to be reciprocated in the other direction than that already referred to and effect reengagement of the pawls with the ratchet-wheel at the right side of the writing mechanism and disengagement of the pawls at the left side thereof.

It will be readily understood that slot f in cam-plate F governs the outward and inward shifting of slide a^{13} and that while pin h^2 of slide-shifting lever H passes along this cam-slot pin i^2 of feed-reversing lever I is traveling along slot f^2 . This latter slot, it will be seen, is provided with a plurality of stations s' , s^2 , s^3 , and s^4 , which govern successive feed reversals, inasmuch as when pin i^2 occupies stations s' or s^3 the forward end of lever I is raised to its limit of elevation, and the feed-pawl (at the right side of the writing mechanism, say,) is disengaged from its ratchet-wheel, while when the pin stands in stations s^2 or s^4 the forward end of the lever is depressed, and the pawl at such side of the machine is consequently reengaged with the ratchet. Now the slots f and f^2 are so arranged that when slide a^{13} is shifted, as illus-

trated in Figs. 3 and 8, to position region R' of the ribbon over the printing-point pin i^2 of the feed-reversing lever occupies station s^3 or s^4 , while when the cam-plate F has been 5 swung to protract the slide, so as to carry region R^2 of the ribbon above the printing-point, said pin stands either in station s' or s^2 ; but stations s^3 and s^4 govern feeding of the ribbon in opposite directions, and so do stations 10 s' and s^2 . It follows, therefore, that an axial shifting of the ribbon-carriers to select a different printing-path in the same longitudinal ribbon region causes a reversing of the feed. Also, since, as will be evident, when lever I 15 passes from station s^4 to station s^2 the front path on ribbon region R' is advanced away from the printing-point and the front path on region R^2 is positioned directly above said point, and in like manner when the lever 20 moves from engagement with station s^3 into engagement with station s' the rear path on ribbon region R' is positioned in front of the printing-point and the rear path on region R^2 is carried above such point, and since also 25 stations s^4 and s^2 and stations s^3 and s' govern ribbon-feeding of like direction it follows, further, that axial shifting of the ribbon-carrier to select a corresponding path on a different longitudinal ribbon region may be effected without reversing the feed.

A tube K is loosely fitted on the rocker-shaft G and is shown extending throughout the length of said shaft G between the attaching-points of the cam-plates F at each side of 35 the machine. A depending arm g^2 , rigidly secured at one end on the tube K on the inside of the plate A , carries at its lower end a pin g^3 , engaging a hole g^4 , arranged in a boss g^5 on the slide a^{13} at its lower right-hand corner, as clearly shown in Figs. 1, 2, 3, and 8. Swinging of the arm g^2 turns the tube K . Turning of the transverse rocker-shaft G operates the cam-plate F , which plate in turn operates the bell-crank lever H , and this lever effects actuation of the slide a^{13} , which moves the arm g^2 , connecting with said slide, and the tube K , which latter is rocked by the movement of said arm, and the rocking of said tube moves the depending arm O , which 45 is rigidly secured to the tube and operates the ribbon-guide, as will be more fully described hereinafter. By reason of the connection of the parts with the rocker-shaft G rotation of that shaft swings this arm, and 50 this causes reciprocation of the slide a^{13} to shift the spools and their feeding mechanism, above described, to position them for different path-writing on the ribbon which they carry. The shifting of this slide a^{13} is prefer- 55 ably in consonance with the positioning of the pawls, as already described, so that the feeding of the ribbons may be changed or not, according to the extent of the shifting of the slide.

65 An arm L is rigidly secured to the end of

the rocker-shaft G , Figs. 8, 8^a, 8^b, and 8^c (preferably exteriorly of the side plate A , so as to be of ready access) and carries a detent-pin m' , constructed to engage holes m^3 m^4 in a depending cruciform lever M , arranged under 70 the lever L and rockingly suspended from the rocker-shaft G , the said detent-pin serving to hold said arm L in any one of its several adjusted positions, the arm L being limited in its movement by stops m^3 m^4 on the lever M . 75 It is to be understood that in lieu of the holes in the lever M there may be disposed thereon a series of pins to engage a hole in the arm L .

It will be clear that upon operating the arm L the rocker-shaft G will be turned to 80 swing the cam-plate F , arranged on the opposite side of the plate A and which is secured at the inner end of said rocker-shaft. During such swing of the cam-plates the cam-surface f will rock the bell-crank lever H and 85 simultaneously transmit movement to slide a^{13} to shift the ribbon transversely to a different color of the ribbon (in the direction of its width) and lock same in such shifted position without reversing the feed, as already de- 90 scribed.

The lever M is loosely mounted on the rocker-shaft G between the exterior surface of the side plate A and the arm L , and by the engagement of the detent-pin m^5 thereon 95 with the holes m^{3x} m^{4x} , formed in the side plate A , the movement of this lever M necessarily carries with it the arm L , which, being rigid upon the rocker-shaft G , causes it to turn the said shaft to a lesser degree than 100 when the arm L is moved independent of the lever M . The relative distance between holes m^3 m^4 and m^{3x} m^{4x} and the relative lengths of the levers between their axes and pins m^3 m^4 are such that lever M turns shaft G through 105 a shorter arc than does lever L . As will be understood, the movement of the arm L may be effected independent—that is, without movement—of the lever M , and movement of this arm L is sufficiently great to effect 110 a considerable rotation of the rocker-shaft G , so that the shifting of the ribbon-spools shall be effected without reversing the feed, as already described. The movement, however, of the lever M simply moves the 115 arm L , but to a less extent than is above described, so that while the ribbon-spools will be shifted it will be only for a short distance, and by the arrangement already described the reversing of the feed will be effected. 120

Levers M and L , by reason of their respective connections with cam-plate F and carrier-shifting lever H and feed-reversing lever I , may be regarded as constituting, respectively, means for shifting the ribbon widthwise to any one of a plurality of paths of the same ribbon region and simultaneously reversing the feed and means for shifting the ribbon from a path on one region to a corresponding path on another region without re- 125 130

versing the feed, lever M shifting the ribbon to a less extent than does lever L. Another conception that grows out of the last is that lever L serves as means connected with the feed-reversing mechanism for shifting the ribbon element widthwise, while lever M constitutes distinct though associated means for shifting the ribbon for a shorter distance. These functions inhere in the two levers, since 5 lever M causes carrier-shifting lever H to travel a short distance along slot f and lever I simultaneously to pass between adjacent stations in cam-slot f², while lever L causes lever H to move a greater distance along slot f at the same time that lever I is passing between alternate stations in slot f².

It is to be understood that I may have more than two holes in the arm L and in the side plate A, thus providing for more than 10 the four shifts illustrated in Fig. 8 *et seq.*

A knob A² may be provided on each spool to permit rapid and easy winding of the ribbon from one spool to the other.

My invention, in connection with the shifting of the ribbon carriers or spools, is to be distinguished from others in the art wherein there is a temporary shifting only of the spools or ribbon merely for throwing a red ribbon into position.) In my arrangement 15 the spools are shiftable into one or more rest positions—that is, positions in which the spools remain permanently or until shifted to a different position.

Ribbon-guide.—Figs. 1, 2, 4, 5, 6, and 7 show a ribbon-guide N, constructed to support and position that portion of the ribbon adjacent to the printing-point and to elevate the ribbon away from said printing-point upon release of a key-lever after printing any 20 character in order that a "visible" system of type-writing may be provided. This ribbon-guide is so arranged as to be shifted also when the ribbon-spools are shifted to secure a different path thereon, as will presently be 25 described. A yoked or forked ribbon-guide N is provided with an opening sufficiently large to embrace the printing-space of the machine and carries guide-strips n, which are 30 constructed to hold the ribbon against the guide N. Secured upon the under side of the guide N are presser-arms n¹, preferably formed of thin spring metal and provided to prevent creeping or bulging of the paper at the printing-point, more particularly de- 35 scribed and claimed in my pending applica- 40 tion, filed February 19, 1904, Serial No. 194,396. A plate n², to which the guide is connected at its rear end, is shown slidably supported on the lower face of the type- 45 writer frame for a back-and-forth movement in a direction at an angle to the path of feed of the ribbon. To the ribbon-guide N is secured an arm n³, fulcrumed to the plate n² and pivotally connected to one end of a lever 50 n⁴, the other end n⁵ of said lever being con-

nected by a bell-crank lever n⁷ to the lever n⁸. The bell-crank lever n⁷ is fulcrumed on an upright post n⁹, carried by the sliding plate n⁸. An arm n¹⁰ is pivotally connected to the upper forked end n¹¹ of the lever n⁸ and is rockingly supported on the transverse rod D and arranged so that the projecting finger portion n¹² bears upon or approximately upon the under side of and is moved by the universal bar E when the same is operated by 70 the actuation of a type-bar. A spring n¹³ is attached to the rear end of arm n¹⁰ for returning same to its normal position after actuation.

Figs. 1, 2, and 4 show the ribbon-guide N 80 in its normal or raised position, in which the ribbon is elevated to render the writing visible. Upon depression of any key-lever the universal bar E will be depressed and move the guide N into its lower operative position, 85 in which it is ready to receive the printing impact of the type, as shown in Figs. 6 and 7, and upon return of the universal bar E to its normal upper position after release of the key-lever the ribbon-guide N will be raised to 90 its normal position. It is to be understood that the ribbon-guide-operating arm n¹⁰ need not return to full normal position before the universal bar is again operated in rapid writing, they not being in direct connection one 95 with the other. As will be readily understood, I may utilize any other form of device or arrangement adapted to the purpose to give the necessary play and secure the same function as that just described.

Of course when the ribbon is shifted widthwise it is expedient also to shift the ribbon-guide N for its proper operation, as shown in Figs. 1, 2, and 5.

The arm O, already referred to as rigidly 105 secured to the tube K, carries at its lower end a stud o, engaging a slot o² in the post n⁹. It will be clear that by this construction the tube K will be turned by the arm g², secured thereto, as already described, when the ribbon-spools are shifted, and that the arm O, being thus also secured to the tube K, will 110 swing and shift the slide-plate n⁸ to position the ribbon-guide N into proper place relative to the ribbon-spools.

The ribbon-guide is arranged to hold the ribbon taut when in its proper normal position and on the beginning of its descent to slacken the ribbon, and thereby reduce the pull on the ribbon-feed mechanism. As the 120 ribbon-guide continues to descend it acts properly to position the ribbon and to hold it against any movement until the type has struck, thereby avoiding danger of blurring the writing or filling the face of the type with 125 ink or lint.

A carriage-escapement or letter-spacing mechanism P is arranged on the carriage and connects with the universal bar E, and by reason of the fact that the ribbon-guide is not 130

directly connected to the universal bar and does not therefore have to be operated at each stroke of a printing-bar the operation of this escapement mechanism is greatly facilitated 5 in rapid writing.

The rocker-block p of the letter-spacing mechanism carries an extending-plate p^1 , twisted longitudinally near its center p^3 , as shown, and having its outer end reduced and 10 cut out at each side to form a T-shaped holder p^4 . Upon this holder is detachably disposed the upper slotted end p^5 of a depending connecting-link p^6 , into which is threaded the upper screw-threaded end of an arm p^7 , 15 the lower end p^8 of which arm is attached to the universal bar E . It will be understood that the movement of the universal bar oscillates said arm p^7 and its connecting-link p^6 and by-reason of the connection of the latter 20 with the plate p^2 rocks the escapement mechanism to position one or the other of its dogs p^9 p^{10} into and out of engagement with the rack-bar p^{11} disposed contiguous thereto.

Arranged beneath the ribbon-spools and 25 preferably in juxtaposition thereto are posts or idlers Q , which serve to facilitate feeding and positioning of the ribbon when the ribbon-guide moves toward or away from the printing-point.

It is to be understood that the parts herein 30 shown and described as constituting features of my invention are preferably adjustably arranged, so that they may be adjusted at will to effect better or more or less extended 35 movement as desired or expedient or to take up or allow lost motion, and to this end adjusting-screws are conveniently disposed, as shown.

It is to be understood that this invention 40 may be arranged to apply to any type-writing machine without departing from the spirit of the same.

Having described my invention, what I 45 claim, and desire to secure by Letters Patent, is—

1. In a type-writer, the combination with a writing mechanism, a ribbon element constituted of a plurality of longitudinal regions, and carriers for said element; of means for 50 shifting said element widthwise to position for writing different writing-paths on any of said regions, and means for shifting the ribbon element to position different regions for writing.

55 2. In a type-writer, the combination with a writing mechanism, a ribbon element formed of a plurality of differentiated longitudinal regions, and carriers for said element; of operating means for shifting said ribbon 60 element widthwise to carry different writing-paths on any one of said regions over the printing-point, and distinct but associated operating means for shifting the ribbon element to carry different regions over the 65 printing-point.

3. In a type-writer, the combination with a writing mechanism, a ribbon element comprising a plurality of longitudinal regions, and carriers for said elements rotatable for effecting feeding thereof; of means for shifting 70 said carriers axially to carry different writing-paths on any one of said regions over the printing-point, and means for shifting said carriers to carry different regions over the printing-point. 75

4. In a type-writer, the combination with a writing mechanism, a ribbon element comprising a plurality of longitudinal regions, opposed carriers for said element, and an intermediate ribbon-guide; of means for shifting 80 said ribbon element to carry the different writing-paths on any one of said regions over the printing-point, and means for shifting said guide to carry different regions over the printing-point. 85

5. In a type-writer, the combination of a writing mechanism, a ribbon element embracing a plurality of longitudinal regions, opposed carriers rotatable for effecting feeding of said element, and an intermediate ribbon-guide; of means for shifting said carriers and said guide simultaneously to carry different writing-paths on any of said regions over the printing-point, and means for shifting 90 said carriers and guide to carry different regions over the printing-point. 95

6. In a type-writer, the combination with a writing mechanism, a ribbon element comprising a plurality of longitudinal regions, and carriers for said element; of means for 100 shifting said ribbon element widthwise to carry different writing-paths on any of said regions over the printing-point, means for shifting the ribbon element to carry different regions over the printing-point, and means 105 for retaining the ribbon element at its several shifted positions.

7. In a type-writer, the combination with a writing mechanism, a ribbon element comprising a plurality of longitudinal regions, 110 and means for feeding said element longitudinally; of means for shifting said ribbon element widthwise to carry different writing-paths on any of said regions over the printing-point, and means for shifting the ribbon 115 element to carry different regions over the printing-point.

8. In a ribbon mechanism, the combination with a ribbon element comprising a plurality of longitudinal regions, means for feeding said element, and means for reversing the feed thereof; of means for shifting said ribbon element widthwise carrying different writing-paths on any of said regions over the printing-point and reversing the feed, and 125 means for shifting the ribbon element carrying different regions over the printing-point without reversing the feed. 130

9. In a ribbon mechanism, the combination with a ribbon element comprising a plu-

rality of longitudinal regions, and with ribbon-feed mechanism; of operating means for shifting said ribbon element widthwise carrying different writing-paths on any of said regions over the printing-point and reversing the feed, and distinct but associated operating means for shifting the ribbon element carrying different regions over the printing-point without reversing the feed.

10. In a ribbon mechanism, the combination with a ribbon element constituted of a plurality of longitudinal regions, opposed carriers for said element, an intermediate ribbon-guide, and ribbon-feed mechanism; of means for shifting said carriers and said guide simultaneously to carry different writing-paths on any of said regions over the printing-point and reversing the feed, and means for shifting said carriers and said

guide to carry different regions over the printing-point without reversing the feed.

11. In a ribbon mechanism, the combination with a ribbon element, and with means for feeding said element longitudinally; of operating means for shifting the ribbon element widthwise over the printing-point and reversing the feed, and distinct but associated operating means for shifting said element without reversing the feed.

12. In a ribbon mechanism, the combination with a ribbon element, and with feed mechanism; of means for shifting said element widthwise to carry different writing-paths over the printing-point, and distinct but associated means for shifting said element to other paths without reversing the feed.

13. In a ribbon mechanism, the combination with a ribbon element, and carriers therefor rotatable for ribbon-feed; of means for shifting said carriers axially to position different writing-paths over the printing-point, and distinct but associated means for shifting said carriers to position other paths over the printing-point.

14. In a ribbon mechanism, the combination with a ribbon element, and with ribbon-carriers rotatable for effecting longitudinal feed thereof; of means for shifting said carriers axially and reversing the feed, and distinct but associated means for shifting said carriers axially without reversing the feed.

15. In a ribbon mechanism, the combination with a ribbon element, and with rotatable carriers therefor; of means for shifting said carriers axially positioning different writing-paths over the printing-point and reversing the feed, and distinct but associated means for shifting said carriers to position other paths over the printing-point without reversing the feed.

16. In a ribbon mechanism, the combination with a ribbon element, opposed carriers rotatable to effect feeding thereof, and an intermediate ribbon-guide; of means for shift-

ing said guide transversely of the travel of the ribbon positioning different writing-paths over the printing-point and reversing the feed, and distinct but associated means for shifting said guide to position other paths over the printing-point without reversing the feed.

17. In a ribbon mechanism, the combination with a ribbon element, opposed carriers rotatable to effect feeding thereof, and an intermediate ribbon-guide; of means for shifting said carriers and guide transversely of the travel of the ribbon element positioning different writing-paths over the printing-point and reversing the feed, and distinct but associated means for shifting said carriers and guide to position other paths over the printing-point without reversing the feed.

18. In a ribbon mechanism, the combination with a ribbon element, and carriers therefor; of operating means for shifting said element widthwise to different rest positions, and additional operating means for actuating said other means to shift said ribbon element widthwise for a shorter distance.

19. In a ribbon mechanism, the combination with a ribbon element, and ribbon-feed mechanism; of operating means for shifting said element widthwise to different rest positions without reversing the feed, and additional operating means for actuating said other means to shift said element widthwise for a shorter distance and to reverse the feed.

20. In a ribbon mechanism, the combination of a ribbon element formed of a plurality of longitudinal regions, and carriers for said elements; of operating means for shifting said ribbon element widthwise to position different writing-paths on any one of said regions over the printing-point, and additional operating means for actuating said other means to shift the ribbon element to carry different regions over the printing-point.

21. In a ribbon mechanism, the combination of a ribbon element formed of a plurality of longitudinal regions, carriers therefor, operating means for shifting said element widthwise to position different regions over the printing-point without reversing the feed, and additional operating means for actuating said other means to shift the ribbon element to position different writing-paths on any of the regions over the printing-point and reversing the feed.

22. In a ribbon mechanism, the combination with a ribbon element, and carriers therefor; of operating means for shifting said element widthwise to different rest positions, and additional operating means carrying said other means and arranged to actuate the latter to shift said element widthwise for a shorter distance.

23. In a ribbon mechanism, the combination with a ribbon element, and carriers therefor; of operating means for shifting said

- element widthwise to different rest positions, and additional operating means carrying said other means and arranged to remain stationary independent thereof but movable 5 to actuate the same to shift the ribbon element widthwise for a shorter distance.
24. In a ribbon mechanism, the combination with a ribbon element, and ribbon-feed mechanism; of operating means for shifting 10 said element widthwise to different rest positions without reversing the feed, and additional operating means carrying said other means and arranged to remain stationary independent thereof but movable to actuate 15 the same to shift the ribbon element widthwise for a shorter distance and to reverse the feed.
25. In a ribbon mechanism, the combination with a ribbon element constituted of a 20 plurality of longitudinal regions, and with ribbon-feed mechanism; of operating means for shifting said element widthwise to position different regions over the printing-point without reversing the feed, and additional 25 operating means carrying said other means and arranged to remain stationary independent thereof but movable to actuate the same to shift the ribbon element widthwise to position different writing-paths on any of the 30 regions over the printing-point and to reverse the feed.
26. In a ribbon mechanism, the combination with a ribbon element, ribbon-feed mechanism, and ribbon-reverse mechanism; 35 of operating means connected with said reverse mechanism for shifting said element widthwise to different rest positions, and additional operating means for actuating said other means to shift the ribbon element 40 widthwise for a shorter distance.
27. In a ribbon mechanism, the combination with a ribbon element constituted of a plurality of longitudinal regions, and with ribbon-feed mechanism; of means for shifting 45 said ribbon element widthwise a certain distance to position different regions over the printing-point, and means for shifting said element to position different writing-paths on any of said regions over the printing-point.
28. In a ribbon mechanism, the combination with a ribbon element constituted of a plurality of longitudinal regions, and with ribbon-feed mechanism; of means for shifting 55 said ribbon element widthwise to position different writing-paths on any of said regions over the printing-point, and means for shifting said element a certain distance to position corresponding paths on different regions over the printing-point.
29. In a ribbon mechanism, the combination with a ribbon element constituted of a 60 plurality of longitudinal regions, ribbon-feed mechanism, and ribbon-reverse mechanism; 65 of means for shifting said element a certain distance widthwise to position different regions over the printing-point without reversing the feed, and means for shifting the ribbon element to position different writing-paths on the same region over the printing-point and to reverse the feed. 70
30. In a ribbon mechanism, the combination of a ribbon element constituted of a plurality of longitudinal regions, ribbon-feed mechanism, and ribbon-reverse mechanism; 75 of means for shifting said element a certain distance widthwise to position different regions over the printing-point without reversing the feed, and associate means for shifting the ribbon element to position different writing-paths on any of said regions over the printing-point and to reverse the feed. 80
31. In a type-writer, ribbon-carriers, a multicolored ribbon carried thereby and each 85 color thereof constituted of a width to present a plurality of paths, means for feeding said ribbon between its carriers, means for reversing such feed, means for shifting the ribbon widthwise to present a different path 90 at the printing-point and simultaneously effecting a reversal of the feed, means for effecting shifting of the ribbons widthwise to present a different color at the printing-point and constructed to effect such function without reversing the feed, writing mechanism, a ribbon-guide constructed and arranged to position the ribbon at the printing-point after each operation of the writing mechanism to give visibility along the printing-line. 95
32. In a ribbon mechanism, the combination with a ribbon element, ribbon-feed mechanism, and a ribbon-reversing member; of a cam-surface provided with a plurality of stations governing feed reversals and adapted to 100 be engaged by said member, means for causing said member to pass between adjacent stations on the cam-surface, and means for causing said member to pass between alternate stations. 105
33. In a ribbon mechanism, the combination with a ribbon element, ribbon-feed mechanism, and a feed-reversing member; of a movable cam-surface engaged by said member and provided with a plurality of stations 110 governing feed reversals, means for moving said cam-surface to cause the feed-reversing member to pass between adjacent stations, and means for moving the cam-surface to cause said member to pass between alternate 115 stations. 120
34. In a ribbon mechanism, the combination with a ribbon element, ribbon-feed mechanism, and a feed-reversing member; of a movable cam-surface engaged by said member and provided with a plurality of stations 125 governing feed reversals, means for moving said cam-surface to cause the feed-reversing member to pass between adjacent stations, and associated means for moving the cam- 130

surface to cause said member to pass between alternate stations.

35. In a ribbon mechanism, the combination with a ribbon element, ribbon-feed mechanism, and a feed-reversing member; of a cam-surface provided with a plurality of stations governing feed reversals, operating means for causing said feed-reversing member to pass between alternate stations, and additional operating means for actuating said other means to cause said member to pass between adjacent stations.

36. In a ribbon mechanism, the combination with a ribbon-carrier rotatable for ribbon-feed and shiftable axially, a feed-reversing member, and a cam-surface engaged by said member and provided with a plurality of stations governing feed reversals; of means for causing said member to pass between adjacent stations during shifting of the carrier, and means for causing said member to pass between alternate stations during shifting of the carrier.

37. In a ribbon mechanism, the combination with a ribbon-carrier rotatable for ribbon-feed and shiftable axially, a feed-reversing member, and a cam-surface engaged by said member and provided with a plurality of stations governing feed reversals; of common means for shifting the ribbon-carrier and causing said feed-reversing member to pass between like stations on the cam-surface, and common means for shifting said carrier a shorter distance and causing said member to pass between unlike stations.

38. In a ribbon mechanism, the combination with a ribbon-carrier rotatable for ribbon-feed and shiftable axially, a feed-reversing member, and a cam-surface engaged by said member and provided with a plurality of stations governing feed reversals; of common operating means for shifting the ribbon-carrier and causing said feed-reversing member to pass between like stations on the cam-surface, and additional operating means for actuating said other means to shift the carrier a shorter distance and to cause said member to pass between unlike stations.

39. In a ribbon mechanism, the combination with a rotatable and axially-shiftable ribbon-carrier, a feed-reversing member, and a cam-surface engaged by said member and provided with a plurality of stations governing feed reversals; of common operating means for shifting the ribbon-carrier and causing said feed-reversing member to pass between like stations on the cam-surface, and additional operating means carrying said other means and arranged to remain stationary independent thereof but movable to actuate the same to shift the carrier a shorter distance and to cause said member to pass between unlike stations.

40. In a ribbon mechanism, the combina-

tion of a rotatable ribbon-carrier, a ribbon-carrier support shiftable axially of said carrier, a swinging cam member having a camway, a support-shifting member connecting said carrier-support and said camway, said cam member being provided with a second camway having a plurality of stations governing feed reversals, a feed-reversing member engaging said second camway, operating means for swinging said cam member to cause said feed-reversing member to pass between alternate stations, and associated means for swinging the cam member to cause said feed-reversing member to pass between adjacent stations.

41. In a ribbon mechanism, the combination of a rotatable ribbon-carrier, a shiftable carrier-support, a swinging cam member having a camway, a bell-crank lever connecting said carrier-support and said camway, said cam member being provided with a second camway having a plurality of stations governing feed reversals, a feed-reversing lever engaging said second camway, operating means for swinging said cam member to cause said feed-reversing member to pass between alternate stations, and additional operating means for actuating said other means to swing the cam member a less distance to cause said feed-reversing member to pass between adjacent stations.

42. In a ribbon mechanism, the combination of a rotatable ribbon-carrier, a ratchet-wheel connected therewith, a shiftable member, a support member therefor, a locking-pawl mounted on said support member and arranged to be shifted out of operative relation to said ratchet-wheel by said shiftable member, and a feed-pawl mounted on said shiftable member and movable therewith into and out of operative relation with the ratchet-wheel.

43. In a ribbon mechanism, the combination of a rotatable ribbon-carrier, a ratchet-wheel connected therewith, a shiftable member, a support member therefor, a locking-pawl mounted on said support member and arranged to be shifted out of operative relation to said ratchet-wheel by said shiftable member, means for restoring the locking-pawl to operative position, and a feed-pawl mounted on and shiftable with said shiftable member into and out of operative relation to the ratchet-wheel.

44. In a ribbon mechanism, the combination of a rotatable ribbon-carrier, a ratchet-wheel connected therewith, a shiftable member, a support member therefor, a locking-pawl mounted on said support member and arranged to be shifted out of operative relation to the ratchet-wheel by said shiftable member and to be restored to operative position independent thereof, and a feed-pawl movable on said shiftable member to effect

rotation of the ratchet-wheel and shiftable member into and out of operative relation to the ratchet-wheel.

45. In a ribbon mechanism, the combination of a rotatable ribbon-carrier, a ratchet-wheel connected therewith, a shiftable member, a support therefor, a locking-pawl mounted on said support member and arranged to be shifted out of operative relation to the ratchet-wheel by said shiftable member, an oscillating arm pivoted to said shiftable member, and a feed-pawl carried by said arm.

46. In a ribbon mechanism, the combination of a rotatable ribbon-carrier, a ratchet-wheel connected therewith, a shiftable member, a locking-pawl arranged to be shifted out of operative relation to the ratchet-wheel by said shiftable member, an oscillating arm pivoted to said member, and a feed-pawl carried by said arm.

47. In a ribbon mechanism, the combination of a rotatable ribbon-carrier, a ratchet-wheel connected therewith, a locking-pawl, a shiftable member, an arm pivoted to said member, a feed-pawl carried by said arm, means for oscillating said arm to rotate said wheel, and means for shifting said member to carry said pawls out of operative relation to the ratchet-wheel.

48. In a type-writer, a ribbon-carrier shiftable to different operative rest positions, a slide upon which the carrier is rotatably mounted, means for reciprocating said slide to position the carrier in one of a plurality of its rest positions, a ratchet-wheel connecting with the carrier, a shiftable plate movably supported on said slide, a feeding-pawl connecting with said shiftable plate, a locking-pawl arranged contiguous to said feeding-pawl, means carried by the slide and engaging the shiftable plate for effecting its reciprocation to engage and disengage the pawls with the ratchet-wheel, and means connecting with said feeding-pawl to oscillate it to effect rotation of the ratchet-wheel and carrier.

49. In a type-writer, a ribbon-carrier, a slide upon which the carrier is rotatably mounted, means for reciprocating said slide to position the carrier in one of a plurality of positions, a ratchet-wheel connecting with the carrier, a shiftable plate disposed on said slide, a pivoted feed-pawl arm, carried by and movable with said plate, a feeding-pawl disposed upon and operated by pivoted arm, a locking-pawl arranged contiguous to said feeding-pawl, means carried by the slide and engaging the shiftable plate for effecting its reciprocation to engage and disengage the pawls with the ratchet-wheel, and means connecting with said feeding-pawl to oscillate it to effect rotation of the ratchet-wheel and carrier.

50. In a type-writer, a ribbon-carrier, a slide upon which the carrier is rotatably mounted, means for reciprocating said slide to position the carrier in one of a plurality of positions, a ratchet-wheel connecting with the carrier, a shiftable plate disposed on said slide, a feeding-pawl connecting with said slide, an idler-bracket disposed contiguous to said slide, a locking-pawl disposed on said bracket, means carried by the slide and engaging the shiftable plate for effecting its reciprocation to engage and disengage the pawls with the ratchet-wheel, and means connecting with said feeding-pawl to oscillate it to effect rotation of the ratchet-wheel and carrier.

51. In a type-writer, a ribbon-carrier, a slide upon which the carrier is rotatably mounted, means for reciprocating said slide to position the carrier in one of a plurality of positions, a ratchet-wheel connecting with the carrier, a shiftable plate disposed on said slide, a feeding-pawl connecting with said slide, an idler-bracket disposed contiguous to said slide, a locking-pawl disposed on said bracket, means carried by the shiftable plate and constructed and arranged to position said locking-pawl relative to the ratchet-wheel, means carried by the slide and engaging the shiftable plate for effecting its reciprocation to engage and disengage the pawls with the ratchet-wheel, and means connecting with said feeding-pawl to oscillate it to effect rotation of the ratchet-wheel and carrier.

52. In a type-writer, a ribbon-carrier, a slide upon which the carrier is rotatably mounted, means for reciprocating said slide to position the carrier in one of a plurality of positions, means for slidably supporting said slide, a ratchet-wheel connecting with the carrier, a shiftable plate disposed on said slide, a feeding-pawl connecting with said slide, a locking-pawl arranged contiguous to said feeding-pawl, means carried by the slide and engaging the shiftable plate for effecting its reciprocation to engage and disengage the pawls with the ratchet-wheel, and means connecting with said feeding-pawl to oscillate it to effect rotation of the ratchet-wheel and carrier.

53. In a type-writer, a ribbon-carrier, a slide upon which the carrier is rotatably mounted, means for reciprocating said slide to position the carrier in one of a plurality of positions, a ratchet-wheel connecting with the carrier, and supported on, and movable with, said slide, a shiftable plate disposed on said slide, a feeding-pawl connecting with said slide, a locking-pawl arranged contiguous to said feeding-pawl, means carried by the slide and engaging the shiftable plate for effecting its reciprocation to engage and disengage the pawls with the ratchet-wheel,

- and means connecting with said feeding-pawl to oscillate it to effect rotation of the ratchet-wheel and carrier.
54. In a type-writer, a ribbon-carrier, a slide upon which the carrier is rotatably mounted, means for reciprocating said slide to position the carrier in one of a plurality of positions, comprising a cam-plate, a lever connecting with said cam-plate and said slide, means for effecting movement of said cam-plate, a ratchet-wheel connecting with the carrier, a shiftable plate disposed on said slide, a feeding-pawl connecting with said slide, a locking-pawl arranged contiguous to said feeding-pawl, means carried by the slide and engaging the shiftable plate for effecting its reciprocation to engage and disengage the pawls with the ratchet-wheel, and means connecting with said feeding-pawl to oscillate it to effect rotation of the ratchet-wheel and carrier. 75
55. In a type-writer, a ribbon-carrier, a slide upon which the carrier is rotatably mounted, means for reciprocating said slide to position the carrier in one of a plurality of positions, comprising a cam-plate, a lever connecting with said cam-plate and said slide, a bell-crank lever engaging said cam-plate and the slide, means for effecting movement of said cam-plate, a ratchet-wheel connecting with the carrier, a shiftable plate disposed on said slide, a feeding-pawl connecting with said slide, a locking-pawl arranged contiguous to said feeding-pawl, means carried by the slide and engaging the shiftable plate for effecting its reciprocation to engage and disengage the pawls with the ratchet-wheel, and means connecting with said feeding-pawl to oscillate it to effect rotation of the ratchet-wheel and carrier. 80
56. In a type-writer, a ribbon-carrier, a slide upon which the carrier is rotatably mounted, means for reciprocating said slide to position the carrier in one of a plurality of positions, comprising a cam-plate, a lever connecting with said cam-plate and said slide, means for effecting movement of said cam-plate, consisting of arms, a shaft with which said arms engage, a ratchet-wheel connecting with the carrier, a shiftable plate disposed on said slide, a feeding-pawl connecting with said slide, a locking-pawl arranged contiguous to said feeding-pawl, means carried by the slide and engaging the shiftable plate for effecting its reciprocation to engage and disengage the pawls with the ratchet-wheel, and means connecting with said feeding-pawl to oscillate it to effect rotation of the ratchet-wheel and carrier. 85
57. In a type-writer, a ribbon-carrier, a slide upon which the carrier is rotatably mounted, means for reciprocating said slide to position the carrier in one of a plurality of positions, comprising a cam-plate, a lever connecting with said cam-plate and said slide, a ratchet-wheel connecting with the carrier, a shiftable plate disposed on said slide, a feeding-pawl connecting with said slide, a locking-pawl arranged contiguous to said feeding-pawl, means carried by the slide and engaging the shiftable plate for effecting its reciprocation to engage and disengage the pawls with the ratchet-wheel, and means connecting with said feeding-pawl to oscillate it to effect rotation of the ratchet-wheel and carrier. 90
58. In a type-writer, a ribbon-carrier, a slide upon which the carrier is rotatably mounted, means for reciprocating said slide to position the carrier in one of a plurality of positions, a ratchet-wheel connecting with the carrier, a shiftable plate disposed on said slide, a pivoted feed-pawl arm carried by and movable with said plate, a feeding-pawl disposed upon and operated by said pivoted arm, means for effecting movement of said feed-pawl arm and pawl to rotate the ratchet-wheel, a locking-pawl arranged contiguous to said feeding-pawl, and means carried by the slide and engaging the shiftable plate for effecting its reciprocation to engage and disengage the pawls with the ratchet-wheel. 95
59. In a type-writer, a ribbon-carrier, a slide upon which the carrier is rotatably mounted, means for reciprocating said slide to position the carrier in one of a plurality of positions, a ratchet-wheel connecting with the carrier, a shiftable plate disposed on said slide, a pivoted feed-pawl arm carried by and movable with said plate, a feeding-pawl disposed upon and operated by said pivoted arm, means for effecting movement of said feed-pawl arm and pawl to rotate the ratchet-wheel, a locking-pawl arranged contiguous to said feeding-pawl, and means carried by the slide and engaging the shiftable plate for effecting its reciprocation to engage and disengage the pawls with the ratchet-wheel, said means comprising a feed-pawl-operating lever, a link connecting therewith, and a universal bar for operating said link. 100
60. In a type-writer, a ribbon-carrier, a slide having an angular extending portion upon which the carrier is rotatably mounted, means for reciprocating said slide to position the carrier in one of a plurality of positions, a ratchet-wheel connecting with the carrier, a shiftable plate disposed on said slide, a feeding-pawl connecting with said slide, a locking-pawl arranged contiguous to said feeding-pawl, means carried by the slide and engaging the shiftable plate for effecting its reciprocation to engage and disengage the pawls with the ratchet-wheel, and means connecting with said feeding-pawl to oscillate it to effect rotation of the ratchet-wheel and carrier. 105
61. In a type-writer, a ribbon-carrier, a slide upon which the carrier is rotatably mounted, means for effecting reciprocation 110

- of the slide to shift the carrier to one of a plurality of positions, a universal bar, means connecting therewith and with the carrier for rotating the same, a ribbon-guide, means operated by the universal bar for oscillating the ribbon-guide, and means deriving movement from the reciprocation of the slide for effecting shifting of the ribbon-guide, substantially as described.
62. In a type-writer, the combination with a writing mechanism, of shiftable ribbon-carriers disposed on said writing mechanism, a universal operating-bar actuated by the writing mechanism, means deriving movement from the operating-bar to rotate said carriers to wind the ribbon, a ribbon-guide, means for simultaneously shifting the ribbon-carriers and guide widthwise to shift the ribbon to one of its writing-paths, said means operating, also, to effect additional shifts of the ribbon-carriers and guide widthwise to shift the ribbon to other of its writing-paths, substantially as described.
63. In a type-writer, the combination with a writing mechanism, of shiftable ribbon-carriers disposed on said writing mechanism, a universal operating-bar actuated by the writing mechanism, means deriving movement from the operating-bar to rotate said carriers to wind the ribbon, a vertically-vibrating, hinged ribbon-guide, means for simultaneously shifting the ribbon-carriers and guide widthwise to shift the ribbon to one of its writing-paths, said means operating, also, for simultaneously effecting a plurality of additional shifts of the ribbon-carriers and guide widthwise to shift the ribbon to different writing-paths, substantially as described.
64. In a type-writer, the combination with a writing mechanism, of ribbon-carriers disposed on said writing mechanism, a universal operating-bar actuated by the writing mechanism, means deriving movement from the operating-bar to rotate said carriers to wind the ribbon, a vertically-vibrating, hinged ribbon-guide, means for vibrating the ribbon-guide to and away from the printing-point simultaneously with the feeding of the ribbon mechanism, means for simultaneously shifting the ribbon-carriers and guide widthwise of the ribbon's writing-path, and means for simultaneously effecting a plurality of additional shifts of the ribbon-carriers and guide widthwise of the ribbon's writing-path, substantially as described.
65. In a type-writer, ribbon-carriers, ribbons carried thereby, means for feeding the ribbons comprising a ratchet-wheel arranged contiguous to said carriers, pawls constructed and arranged to have engagement with said ratchet-wheel, and means for positioning said pawls to engage said wheel, and means for effecting disengagement of one of said pawls beyond its point of engagement with

said wheel and constructed to effect a momentary stopping of the feeding of the ribbons at a predetermined point.

66. In a type-writer, ribbon-carriers, a multicolored ribbon carried thereby and each color thereof constituted of a width to present a plurality of paths, means for feeding said ribbon between its carriers, means for reversing such feed, means for shifting the ribbon widthwise to present a different path at the printing-point and simultaneously effecting a reversal of the feed, means for effecting shifting of the ribbons widthwise to present a different color at the printing-point and constructed to effect such function without reversing the feed, and means for locking said several shifting means against movement.

67. In a type-writer, ribbon-carriers, a multicolored ribbon carried thereby and each color thereof constituted of a width to present a plurality of paths, means for feeding said ribbon between its carriers, means for reversing such feed, means for shifting the ribbon widthwise to present a different path at the printing-point and simultaneously effecting a reversal of the feed, means for effecting shifting of the ribbons widthwise to present a different color at the printing-point and constructed to effect such function without reversing the feed, and means for locking said several shifting means against movement in either direction.

68. In a type-writer, ribbon-carriers, a multicolored ribbon carried thereby and each color thereof constituted of a width to present a plurality of paths, means for feeding said ribbon between its carriers, means for reversing such feed, means for shifting the ribbon widthwise to present a different path at the printing-point and simultaneously effecting a reversal of the feed, means for effecting shifting of the ribbons widthwise to present a different color at the printing-point and constructed to effect such function without reversing the feed, and means for locking the feed-reversing means in one of a plurality of positions.

69. In a type-writer, a ribbon-carrier, a slide upon which the carrier is rotatably mounted, means for reciprocating said slide to position the carrier in one of a plurality of positions, comprising a cam-plate, a lever connecting with said cam-plate and said slide, means for effecting movement of said cam-plate, consisting of arms, a shaft with which said arms engage, a ratchet-wheel connecting with the carrier, a shiftable plate disposed on said slide, a feeding-pawl connecting with said slide, a locking-pawl arranged contiguous to said feeding-pawl, means carried by the slide and engaging the shiftable plate for effecting its reciprocation to engage and disengage the pawls with the ratchet-

wheel, means connecting with said feeding-pawl to oscillate it to effect rotation of the ratchet-wheel and carrier, and means for effecting retention of the lever in the cam-
5 plate in one of a plurality of positions.

70. In a type-writer, a flat platen, a traveling downwardly-acting printing mechanism, ribbon-carriers carried by the printing mechanism for sustaining a ribbon, means for effecting movement of the carriers to feed the ribbons, a movable universal bar, connections between the universal bar and said carrier-actuating means, a ribbon-guide depressible to the flat platen, connections between the universal bar and the ribbon-guide and constructed to position the guide at the printing-point on the flat platen, the said connections between the universal bar and the guide being arranged to permit movement of the universal bar independent of such connections, after the guide is positioned at the printing-point, whereby returning of the guide to normal position after each

stroke of the printing mechanism in rapid writing is obviated. 25

71. In a type-writer, a flat platen, a traveling, downwardly-acting printing mechanism, ribbon-carriers for sustaining a ribbon, means for effecting movement of the carriers to feed the ribbons, a movable universal bar, a ribbon-guide, means connecting therewith and engaged by the universal bar for oscillating said guide, escapement mechanism connecting with and actuated by said universal bar, said ribbon-guide-oscillating means being constructed and arranged to effect positioning of the ribbon-guide initially at the printing-point and to prevent its full return to normal position during rapid operation of said printing mechanism. 30
